UNITED STATES PATENT OFFICE.

ROLAND H. GILKERSON, OF WATERTOWN, WISCONSIN, ASSIGNOR OF ONE-FOURTH TO
SOLOMON D. GILKERSON, ONE-FOURTH TO JOHN W. BRENNAN, AND ONE-FOURTH
TO FREDERICK BITTNER, ALL OF WATERTOWN, WISCONSIN.

GARMENT HANGER.

Application filed February 1, 1924. Serial No. 689,993.

To all whom it may concern:

Be it known that I, ROLAND H. GILKERSON, a citizen of the United States, and resident of Watertown, in the county of Jefferson and State of Wisconsin, have invented certain new and useful Improvements in Garment Hangers; and I do hereby declare that the following is a full, clear, and exact description thereof.

10 My invention refers to garment hangers, and has for its primary object to provide a hanger of simple construction with means whereby the garment being supported is firmly held in place but readily detachable from the hanger by a simple manual operation.

The particular object of my invention is to provide a hanger, as above referred to, for the purpose of supporting and displaying delicate garments, such for example as silk waists or the like. Practice has demonstrated that light weight delicate silk garments tend to slip readily upon the standard type of hanger, and under the slightest disturbance, they will drop from the hanger and frequently be seriously damaged by dust or dirt. It is also manifest that where a hanger of the general type referred to above is used and the garment is in effect locked thereon, it will not only hold the garment smoothly and prevent damage, but it will also serve to prevent frequent theft, as it is a common practise for shop lifters or the like to slip delicate garments quickly from the hanger and conceal them.

In my device this cannot be effected until a manual operation is made for releasing the garment from said hanger.

With the above and other objects in view, the invention resides in the novel construction, combination and arrangement of parts substantially as hereinafter described and more particularly defined by the appended claim, it being understood that such changes in the precise embodiment of the herein disclosed invention may be made as come within the scope of the claim.

In the drawing, the single figure illustrates a side elevation of one form of hanger exemplifying my invention, parts being broken away and in section to more clearly illustrate the structural features.

Referring by characters to the drawings 1 represents the bow of a standard wood

garment hanger, and 2 the centrally disposed hanger hook.

The bow is provided with a pair of bearing apertures 3—3 arranged parallel with the hanger hook shank and positioned at equal distances therefrom. These bearing apertures serve as guides for plunger rods 4—4; the upper ends of which rods are folded over above the top face of the bow and thereby form finger extensions 5—5 which are arranged substantially parallel with the top surface of the bow, and which fingers extend a predetermined distance from the ends of the bow, as shown. The finger extensions are preferably jacketed by sections of rubber hose 6—6 or some analogous soft gripping surface which will not injure the garment carried by the hanger.

The arms 4—4 at their lower ends are gently curved and merge into a horizontally disposed gripping bar 7. The arms and gripping bar 7 which, as previously described, are in one piece with the fingers, have mounted thereon a coil spring 8, the upper ends of which coil spring engages the lower surface of the bow, and that portion of the coil spring which surrounds the gripping bar is encased with the sleeve 9, the same being loosely mounted upon said coil spring. This arrangement of one piece coil spring will permit the maximum resiliency of said spring due to the fact that when said coil spring is compressed by manual operation whereby the fingers are freed from contact with the upper surface of the bow, the entire length of coil spring will simultaneously act and will contact and expand in its action throughout both the length of the arms and the gripping bar.

From the foregoing description, it will be understood that when it is desired to affix a garment such as a waist or the like to the hanger, the waist is suspended in the ordinary manner and, prior to its suspension upon the bow, the operator grasps with the finger of one hand the top portion of the bow and the sleeve about the gripping bar. By compressing these two parts, it will be seen that the fingers, which constitute grips, will move a predetermined distance away from the associated surface of the bow, whereby the garment can be conveniently arranged thereupon, and after such arrangement, upon release of the gripping bar, the

spring will cause the fingers or "grips" to assume their normal gripping engagement with relation to the top surface of the bow, whereby the garment is firmly held in position. It will, therefore be seen that the garment cannot be disengaged from its locked relation to the bow until a manual operation is performed to release the fingers or grips. The release of the grips, as previously stated, is effected with one hand while the party displaying the garment can conveniently suspend the same by holding the hanger hook with the fingers of the other hand.

While I have shown and described one exemplification of my invention, it is understood that I may vary the construction of the invention indefinitely within the knowledge of the skilled mechanic, without departing from the spirit of my invention, and it is manifest that in place of utilizing a wooden bow, as shown, a wire substitute can as readily be employed. Furthermore, it is understood that the particular form of grips or fingers may be varied, as for example these fingers may be formed from an inte-

gral flat spring fastened to the center of the bar in which event the plunger rods would be separate elements but would operate in the same way to lift the spring tensioned fingers or grips simultaneously.

30

I claim:

A garment hanger comprising a bow having a pair of spaced apertures adjacent its central portion, a pair of gripping arms located upon the upper side of said bow and conforming thereto, vertical portions integral with said arms passing through said apertures and integrally joined below said bow by a horizontal portion, a coiled spring loosely surrounding said vertical portions and said horizontal portion and bearing at its ends against the under side of said bow, and a sleeve mounted upon the horizontal portion and loosely surrounding a portion of said spring.

45

In testimony that I claim the foregoing I have hereunto set my hand at Watertown, in the county of Jefferson and State of Wisconsin.

ROLAND H. GILKERSON.
